United States Patent Office

Des. 227,277
Patented June 12, 1973

227,277

GAME BOARD

Raymond E. Reilly, 9308 Convento Terrace,
Fairfax, Va. 22030

Filed Sept. 3, 1971, Ser. No. 177,919

Term of patent 7 years

Int. Cl. D21—01

U.S. Cl. D34—5 BG

The figure is a plan view of a game board of conventional thickness showing my new design.

I claim:

The ornamental design for a game board, as shown and described.
